INDUCTOR SWITCH

Harold W. Williams, Nutley, Paul M. Martin, Jersey City, and Donald H. Baum, Ridgewood, N. J., assignors to Westinghouse Electric Elevator Company, Jersey City, N. J., a corporation of Illinois

Application July 26, 1940, Serial No. 347,650

3 Claims. (Cl. 175—336)

Our invention relates to inductor switches and, more particularly, to inductor switches of the character utilized for controlling the acceleration and stopping of elevator cars in elevator systems in which the switches and their coils are mounted on the cars in position to be operated by inductor plates mounted on the hatchway walls.

One object of the invention is to provide an inductor switch which will operate accurately regardless of variations in the exciting current in the switch coil due to coil heating or voltage variations due to the ageing of parts of the system, variable loads on parts of the system or variation in the supply line voltage.

Another object is to provide an inductor switch for elevator cars in which the contact members will operate in exactly the same vertical position relative to the inductor plate regardless of variation in the horizontal distance or air gap between the plate and the switch due to car sway, wear of guide shoes, or other reasons.

A further object is to provide an inductor switch which will use less current than heretofore necessary.

A further object is to provide a narrow, deep and tall form of inductor switch to permit the mounting of a plurality of such switches close together without interfering with each other.

A still further object of our invention is to provide an inductor switch in which the contact members will operate quickly and snappily to prevent excessive contact wear and secure accurate results from the operation of the switch.

It is also an object to provide an inductor switch which may be easily and economically constructed, installed, operated, and maintained in operation.

For a better understanding of the invention, reference may be had to the accompanying drawings, in which:

Figure 1 is a top plan view of an inductor switch embodying our invention mounted on the top of a car in a hatchway;

Fig. 2 is a view in side elevation of the inductor switch illustrated in Fig. 1, with the switch and inductor plate in unoperated position with relation to each other;

Fig. 3 is a view in side elevation of the inductor switch illustrated in Fig. 1 with the inductor plate and switch in their operative position;

Fig. 4 is an enlarged view, in front elevation, of the inductor switch and coil shown and illustrated in Fig. 1;

Fig. 5 is a top plan view of the switch mechanism illustrated in Fig. 4;

Fig. 6 is a view in side elevation of the switch illustrated in Fig. 4;

Fig. 7 is a top plan view of the upper pole plate for the switch illustrated in Fig. 5;

Fig. 8 is a view in side elevation of the upper pole plate illustrated in Fig. 7;

Fig. 9 is a view in front elevation of the upper pole plate of Fig. 8;

Fig. 10 is a top plan view of the operating clip mounted on the armature in Fig. 5;

Fig. 11 is a view in side elevation of the operating clip of Fig. 10;

Fig. 12 is a view in end elevation of the operating clip of Fig. 10;

Fig. 13 is a view in side elevation of the stop clip mounted on the armature in Fig. 5;

Fig. 14 is a view in end elevation of the stop clip of Fig. 13;

Fig. 15 is a top plan view of the cover bracket illustrated in Figs. 5 and 6; and

Fig. 16 is a view in side elevation of the cover bracket of Fig. 15.

Referring more particularly to the drawings, we have illustrated an electromagnetic device such as an inductor switch 1 as mounted on top of a car C in position to be operated by an inductor plate 2 mounted in any suitable manner on the wall 3 of the hatchway in which the car operates. Only a small portion of the car and the hatchway are shown.

The inductor switch comprises a frame 4 of non-magnetizable material, a top plate 5 and a bottom pole plate 6 of magnetizable material mounted on the frame; a core 7 of magnetizable material mounted between the outer ends of the plates, a coil 8 mounted on the core; a pair of switches 9 and 10 disposed on the top pole plate, and a cover 11 and cover bracket 11a for the switches.

40 The frame 4 comprises a hollow rectangular box-like casting provided with a plurality of screw-threaded holes by means of which it may be secured with machine bolts 13 to an angle bracket 14 fastened to the top of the elevator car C by machine bolts 15.

The magnetizable core 7 is of rectangular shape in cross section and is much wider than it is thick. Hence the coil 8 mounted on the core 45 has an oval shape in cross section as shown in Fig. 5, rather than the usual cylindrical form. This permits the use of a narrow form of inductor switch so that a plurality of them may be mounted side by side without taking up a large amount of space. The lower end of the core is

secured in a depression 17 in the bottom pole plate 6 by a pair of machine screws 18. The depression may be made by the operation of a punch press displacing a portion of the plate. The upper end of the core passes through a punched out opening 18a (Fig. 15) in the cover bracket 11a and rests against the underside of the top pole plate 5 to which it is secured by a pair of machine screws 19.

The cover bracket 11a is fastened to the underside of the top pole plate by means of a pair of tubular rivets 20. The outer ends 21 and 22 of the cover bracket are bent upwardly and then turned inwardly to provide supports for the cover 11 which may be fastened thereto by a pair of screws 23.

The rear ends of the top pole plate 5 and the bottom pole plate 6 are securely fixed to the top and bottom of the mounting frame 4 by a plurality of machine screws 24 and 24a (Figs. 5 and 6) so that the frame, the top plate, the cover bracket, the core, the coil, and the bottom plate form a firm structural unit.

The coil 8 is provided with lead wires 25 which extend through an insulating ring 26 in the side of the mounting frame in which they may be connected to a terminal panel (not shown) in the usual manner.

The top pole plate or switch frame 5 (Figs. 7, 8, and 9) is pressed out of heavy magnetizable plate material in somewhat the form of a short handled paddle. It is provided with a pair of holes 27 through which the rivets 20 may extend to hold the plate and the cover bracket firmly together. The plate is also provided with a plurality of holes 28 for the machine screws 24 which hold it on the frame and a plurality of holes 19a for the machine screws 19 passing into the core 7.

When the top plate is shaped, it is provided with a pair of switch-supporting lugs 30 and 31, a pair of lockout lugs 32 and 33 and a pair of armature-supporting lugs 34 and 35.

The switch-supporting lugs 30 and 31 are disposed to the right of the middle of the narrow end 29 of the top plate and are bent upwardly at right angles to the face of the plate. Suitable screw-threaded holes 31 are disposed in the switch lugs to receive machine screws for supporting the switches.

The armature supporting lugs 34 and 35 are located near the central portion of the plate and are bent upwardly at right angles to the plate. The lug 34 is provided with a forwardly extending arm or stationary flux member 34a and the lug 35 is provided with a similar forwardly extending arm or stationary flux member 35a for forming paths for magnetic flux flowing to the armatures to be hereinafter described. The lockout lugs 32 and 33 are disposed on the inner right-hand ends of the plate 5 and are bent upwardly at right angles to the face of the plate but at a slight angle with reference to the edges of the plate. The use of the lugs 32 and 33 will be described later.

The central portion of the paddle end of the plate 5 is cut away at 36 to provide two narrow sections or arms 37 and 38 in the plate. The narrow sections 37 and 38 provide restricted paths for the magnetic flux which may flow from the central portion of the plate to the outer right hand end thereof. The restricted sections 37 and 38 extend into arms 39 and 40 for supporting the lockout lugs 32 and 33. The arms 39 and 40 are braced by the cross piece 39.

The switch 9 (Figs. 4, 5 and 6) comprises a pair of cooperating contact members 41 and 42 mounted on a pair of cooperating spring switch arms 43 and 44 supported in a plurality of insulating sheets 45, which are secured to the lug 31 by a bolster plate 46 and a pair of screws 47. A pair of spacing fingers 48 are also mounted in the stack of insulating sheets in position to limit the movement of the contact arm 44 when the contact members are forced into engagement by the contact arm 43. Two spacing fingers are used to secure a stiff but flexible limiting element. In the present instance it is assumed that the contact members are to remain normally closed except when opened by the operation of the switch mechanism. Therefore the switch arm 43 is bent slightly to bias its contact member 41 into contact with the face of the contact member 42 on the switch arm 44.

The base ends 43a and 44a of the switch arms extend rearwardly from the insulating sheets and are connected to a pair of suitable conductors 50 and 51 for the circuit to be controlled by the switch. The conductors pass from the switch arm ends through an insulating ring 52 into the interior of the frame 4 where they may be connected to a panelboard (not shown). An insulating plug 53 is riveted to the inner side of the outer end of the spring arm 43 to afford a means by which the contact members 41 and 42 may be opened.

An armature 54 is provided for actuating the insulating plug 53 to open the contact members 41 and 42. The armature is an elongated piece of rectangular magnetizable material having its left-hand end pivotally attached to the armature supporting lug 34 by a thin hinge spring 55 and mounted in such position that it extends between the arm 35a and the plate body with its free outer end disposed adjacent to the outer face of the lockout lug 33. The hinge spring 55 may be secured to the armature and its support lug in any suitable manner, as by spot welding. The free end of the armature should not extend to the end of the lockout lug but should extend to about the central portion of the lockout lug, approximately as indicated in Fig. 6. The construction shown has been found to give the best performance in practice.

A stop clip 57 of brass or other suitable non-magnetizable material (Figs. 5, 13 and 14) is spot-welded to the inner side of the free end of the armature 54 in such position that its free end will strike against the inner face of the lockout lug 33 when the armature is in its operated position so as to limit the outward movement of the armature. However, for some operations, it may be more desirable to use an iron stop clip instead of brass in order to secure better operation when self-holding is required.

An operating clip 58 of brass or other suitable non-magnetizable material is also spot-welded to the outer end portion of the armature 54 so that its free end will engage the insulating plug 53 on the arm 43 to cause that arm to move to open position when the armature is actuated. The clip 58 is provided with a central aperture 59 through which the free end of the brass stop clip 57 extends into its stop position with relation to the lockout lug.

In Fig. 5, the position of the various parts of the switch 19 are shown in their normal position when the switch is not being subjected to the influence of an inductor plate, and switch 9 is shown in its operated position under the influence

of the inductor plate 2 when it is in operative position relative thereto and the relay coil 8 is energized.

It should be noted that the spring strength of the switch arm 43 and the position of the outer end of the operating clip 58 should be such that the contact members will be closed and the base of the clip and the armature end will be almost, but not quite, in engagement with the lockout lug 32 when the inductor plate is not near the switch. The parts may be easily adjusted to the correct unoperated position by bending either the switch arm 43 or the clip 58, or both, slightly after the parts are assembled.

Figs. 4 to 16 are practically full-size drawings of the inductor switch. The inductor plate used in practice for this size inductor switch is approximately $\frac{7}{64}$ " thick, 3 to 4" wide, and $7\frac{1}{4}$ " long or longer. The plate should be so mounted in a vertical position on the hatch wall that it will overlap the inductor switch in a horizontal direction a distance of approximately $1\frac{1}{8}$ ", substantially as shown in reduced size in Fig. 1. The plate is so mounted to cause its free side to come near the free end of the armature as the inductor switch passes the plate, for the purpose of securing the most desirable operation of the armature.

An assumed operation of the device follows:

It will be assumed that the car C on which the inductor switch 1 is mounted is disposed in the upper part of its hatchway, that it is moving downwardly in the hatchway and that the coil 8 of the inductor switch has been energized to cause the switch 9 to be opened as the inductor switch comes opposite the inductor plate 2 mounted on the wall of the hatchway.

The energization of the coil 8 energizes the core 7 which causes magnetic flux to pass through the air from one end of the core to the other. The flux paths are very complex and applicants will not attempt to describe them. However, with applicant's structure, the switch will operate as follows. Assume now that the car moves the switch on downwardly until it and the plate are in approximately the position shown in Fig. 2. At this point some of the leakage flux flows from the end of the upper pole plate through the air to the inductor plate, through a portion of the inductor plate and across the air gap between the inductor plate and the bottom pole plate to the lower end of the core. As the switch moves on down along the plate, the flow of flux increases through the plate. This leakage flux starts from the upper end of the core, passes into the center portion of the top plate, thence along the plate where some of it passes into the armature as indicated by the arrow 62. Some part of it flows through the armature supporting lug 35 and along the arm 35a to a point where it crosses the air gap (see arrow 63) between the armature and the arm and then follows the armature. Another portion of the flux flows through the restricted portion 38 of the top plate which causes saturation of the restricted section 38 and results in a considerable drop in magnetic potential between the main part of the top plate and the turned-up lockout lug 33 at the end of the plate. Since the armature has a large ratio of cross-sectional area to air-gap permanence, it is not saturated and has, consequently, a lower drop in magnetic potential from the plate to the end of the armature than appears in the section 38, in spite of the air gap between the plate and the armature. There

is, then, a difference of magnetic potential between the lockout plate and the end of the armature, so that sufficient flux flows from the end of the armature through the small gap to the lockout to produce an appreciable attractive force between the two. This force aids the spring switch arm in holding back against any opening tendency of the armature.

It will be assumed now that the downward movement of the switch has progressed to a point where the upper edge of the inductor plate 2 is horizontally opposite the armature 54 as shown in Fig. 3 and that a greater portion of the flux starts to flow directly from the armature to the plate. This causes the armature 54 to start to move outwardly and it quickly reaches its full open position, as shown in Fig. 5.

When the armature starts to move outwardly, the flux between the armature and the lockout and, consequently, the lockout force, decreases almost immediately to zero, so that, as soon as the armature starts to move, the total force resisting the movement decreases quickly, causing the armature to open the contact members quickly.

This, then, is believed to be the method of causing the snappy contact action set down originally as one of the desirable design features to be sought; for the excess of operating force over restraining force which is built up as soon as motion starts causes the armature to accelerate rapidly and open the contact members quickly. The armature movement without the lockout, with the switch moving slowly past the plate, would be slow and would stop if movement of the switch should stop.

Applicants believe that the above theory as to the flow of flux in their form of inductor switch is correct, but regardless of possible error in the theory, applicants have found in practice that their form of inductor switch uses much less current, that it operates the armature more snappily, and that the switch operates with more accuracy regardless of the horizontal spread between the plate and the armature and regardless of variations in load, voltage, coil heating, etc., than the inductor switches with which they are acquainted.

Although we have illustrated and described only one form of our invention, it is to be understood that changes therein and modifications thereof may be made without departing from the spirit and scope of the invention.

We claim as our invention:

1. In an electromagnetic device, a core, a magnetizing coil disposed on said core, a pole plate of magnetizable material associated with the core, said pole plate having a central body portion and a restricted arm extending from the body portion, an armature-supporting lug extending outwardly from said body portion, a lockout member disposed on said restricted arm; a flux-conducting arm disposed on the armature-supporting lug and extending substantially parallel to the body of the plate and in the direction of the lockout member, an armature disposed between the flux conducting arm and the plate body, and a spring hinge pivotally mounting the armature on the armature-supporting lug with its free end disposed adjacent to the lockout member in position to be actuated by an inductor plate when the coil is energized.

2. In an electromagnetic device, a core, a magnetizing coil disposed on said core, a pole plate of magnetizable material associated with the

core, said pole plate having a central body portion and an arm extending from the body portion, a portion of said arm being of less cross-section than the plate whereby it will be in a magnetic flux saturated condition when the plate is not as the core is energized, an armature having its inner end mounted by a spring hinge between two portions of the pole plate to provide a plurality of magnetic flux paths to the inner end portion of the armature, the outer end portion of said armature being disposed along the arm extending from the plate, and a lockout lug of magnetizable material disposed on one side of the outer end portion of the arm, said lug having a length less than one-half the length of the armature, whereby, under an energized condition of the coil, there will be a difference of magnetic potential between the lockout lug and the armature to attract the armature to the lug.

3. In an electromagnetic device, a core, a magnetizing coil disposed on said core, a pole plate

of magnetizable material associated with the core, said pole plate having a central body portion and a restricted arm extending from the body portion, a magnetizable lug disposed on one side of the outer end portion of the restricted arm, an armature supporting lug extending outwardly from the body portion at approximately right angles to the restricted arm, a flux-conducting arm disposed on the lug and extending substantially parallel to the plate in the direction of the restricted arm, and an armature having its one end portion disposed between the flux-conducting arm and the plate and hingedly mounted on the supporting lug and its other end extending adjacent to the magnetizable lug on the restricted arm in position to be actuated by an inductor plate when the coil is energized.
